[57] CLAIM

The ornamental design for a multi-craft iron, as shown and described.

DESCRIPTION

FIG. 1 is a perspective view of multi-craft iron showing my new design; the broken line showing of the cord is

for environmental purposes only and forms no part of the claimed design;

FIG. 2 is a top plan view of my design;

FIG. 3 is an side elevational view as viewed from the left side in FIG. 2;

FIG. 4 is a front elevational view of my design, with the back elevational view being substantially identical;

FIG. 5 is a side elevational view as viewed from the right side in FIG. 1;

FIG. 6 is a bottom plan view of my design;

FIGS. 7A through 7C illustrate a jewelry applicator tip which is attachable to the "Multi-Craft Iron" of my design, of which FIG. 7B is a side elevational view,

FIG. 7A is an end elevational view as viewed from the left side in FIG. 7B, and FIG. 7C is an end elevational view as viewed from the right side in FIG. 7B; and,

FIGS. 8A through 8C illustrate a stencil cutting tip which is attachable to the "Multi-Craft Iron" of my design, of which FIG. 8B is a side elevational view,

FIG. 8A is an end elevational view as viewed from the left side in FIG. 8B, and FIG. 8C is an end elevational view as viewed from the right side in FIG. 8B.
